CLAIM

The ornamental design for a sign, as shown and described.

DESCRIPTION

FIG. 1 is a front view of the sign. FIG. 2 is a back view of the sign shown in FIG. 1. FIG. 3 is a side view of the sign shown in FIG. 1. FIG. 4 is a front view of another embodiment of the sign. FIG. 5 is a back view of the sign shown in FIG. 4; and, FIG. 6 is a side view of the sign shown in FIG. 4.

The broken lines are included for the purpose of illustrating portions of the sign and form no part of the claimed design.
